UNITED STATES PATENT OFFICE

140,097

DESIGN FOR A JEWELRY CASE

Ernest E. Koch, Forest Hills, N. Y.

Application June 1, 1944, Serial No. 113,826

Term of patent 3½ years

(Cl. D87—3)

To all whom it may concern:

Be it known that I, Ernest E. Koch, a citizen of the United States of America and residing in Forest Hills, New York, have invented a new, original, and ornamental Design for a Jewelry Case, of which the following is a specification, reference being had to the accompanying drawing, forming part thereof.

Fig. 1 is a plan view of a jewelry case in open position, showing my new design; and

Fig. 2 is a front elevational view thereof in closed position.

The back of the case shown is substantially plain.

I claim:

The ornamental design for a jewelry case, as shown and described.

ERNEST E. KOCH.
